WOVEN WIRE BELT FOR PAPER MAKING MACHINES

Harry G. Specht, Montclair, N. J., assignor, by
mesne assignments, to Encor Corporation,
Belleville, N. J., a corporation of New Jersey

Application June 4, 1936, Serial No. 83,519

3 Claims. (Cl. 139—425)

The present invention relates to woven wire belts particularly for paper making machines of the Fourdrinier type. These belts are in the form of a continuous band of fine wire mesh which moves over spaced supporting rolls and in contact with suction boxes and rolls, and it is desirable to provide a wire which will have a relatively long wearing life. These wires are relatively expensive and in normal use have an average life of about twenty days. The cost of changing a wire is great due to lost time in production, so that any increase in the wearing life of the wire is worth a great deal to the paper mills. Another desirable object is to provide a wire having a relatively smooth top surface for the formation of the paper, so as to reduce wire marks as much as possible, while at the same time providing the necessary porosity to permit the water to drain through.

The usual Fourdrinier wire is woven with circular cross-section warp and weft wires, and these not only provide a very small wearing surface at the under side but produce a noticeable mark in the paper. It is proposed in the present invention to provide the warp wires of square cross section, to the end that a larger wearing surface is provided which will remain uniform throughout a longer wearing life, and there is also provided a relatively smooth top surface, while at the same time maintaining equal porosity for a given mesh and wire gauge as the usual type of woven wire having circular cross-section warp wires.

It is further proposed to utilize the sharp corners of the square cross-section warp wires to cause the same to embed into the weft wires through the beating action of the reed, whereby the tops of the weft knuckles are brought nearer to the top surface of the fabric, and the knuckles are more tightly interlocked to prevent sleaziness.

With the above and other objects in view, embodiments of the invention are shown in the accompanying drawings, and these embodiments will be hereinafter more fully described with reference thereto, and the invention will be finally pointed out in the claims.

In the drawings:

Fig. 1 is an enlarged plan view of a portion of a wire belt, according to one embodiment of the invention.

Fig. 2 is a longitudinal sectional view, taken along the line 2—2 of Fig. 1.

Fig. 3 is a transverse sectional view taken along the line 3—3 of Fig. 1.

Fig. 4 is a greatly enlarged transverse section of a small section of the wire showing diagrammatically the comparative wearing surfaces of the wire according to the present invention and

the usual wire having circular cross-section warp wires.

Fig. 5 is a plan view of a portion of a wire belt, having a twill weave according to a modified form of the invention.

Fig. 6 is a longitudinal sectional view, taken along the line 6—6 of Fig. 5.

Fig. 7 is a transverse sectional view, taken along the line 7—7 of Fig. 5.

Figs. 8 to 17 are longitudinal sectional views of further modifications in which modified form of weft wires are employed.

Fig. 18 is an elevation of a piece of twisted cable type weft wire as used in the modifications illustrated in Figs. 12 and 17.

Similar reference characters indicate corresponding parts throughout the several figures of the drawings.

Referring to the drawings, and more particularly to Figs. 1 to 4, the Fourdrinier wire, according to the exemplary illustrated embodiment shown therein, comprises warp wires 10 of square cross-section, and weft wires 11 of circular cross-section, the upwardly bent knuckles of the warp wires providing the upper paper-formation surface and downwardly bent knuckles forming the lower wearing surface.

In the weaving operation the reed hits the weft wires between the warp wires and through the square cross-section of the warp wires the edge 30 of the latter bite into the weft wires, as at 11^a, producing a ridge-like knuckle at the underside, as at 11^b, the reed marks being indicated at 11^c—11^d. In practice the reed mark is produced at a point about 60° to 90° removed from that shown in Fig. 4, the tension applied to the warp, which is greater at one side of the shed than at the other side, causing the weft wire to turn about 60° to 90° bringing the reed mark to the underside of the fabric. It will be seen that the top weft knuckles 11^d are thus brought closer to the paper formation surface, and the bottom weft knuckles 11^b are brought closer to the wear surface, thus making for better paper formation and longer life. Also the biting in of the warp wires with the weft wires interlocks them and prevents sleaziness. In the weaving of a normally loose weave fabric, as for instance twill weave, this interlocking action is particularly effective in preventing the sleaziness which has heretofore been an objection to these weaves.

As seen in Fig. 4 the plane A—A represents the paper formation surface and the plane B—B the lower wearing surface. The dot-and-dash representation of round cross-section warp wires at 12 illustrates the comparative cross-sectional area of round warp wires as compared to the square warp wires of the present invention. The wearing surface is increased to a very great extent at the beginning of wear, the wearing surface being 60

equal to the diameter of the round warp wire when half worn through. As is well known the round warp wires will wear very rapidly at the beginning of wear and when worn to a point where a relatively large wearing surface is provided are so thin that breakage is apt to occur. With the square warp wires of the present invention the wearing surface is not only uniform during the life of the wire but a large wearing surface is provided at the beginning of wear so that the thickness and strength of the warp wires is maintained for a relatively longer period and breakage due to thinning of the knuckles is greatly reduced. Even when half worn through the knuckles have greater strength than the half worn through knuckles of the round cross-section warp wires due to their increased cross sectional area, so that breakage due to excessive wear is practically eliminated. The depressed knuckles of the weft wire prevent wear upon the warp knuckles to a point where the latter are actually worn through, whereas straight weft wires would permit the warp wires to wear through completely. It has been estimated that the cross-sectional area of the square warp wires is approximately 28% greater than the round wires of the same gauge, and the increase in wearing life over round wires is from 25% to 100%. Considering the paper-formation side of the wire it will be seen that the distance between the centers of the round cross-section wires represented by the line 13 is considerably greater than the distance between the adjacent sides of the square cross-section warp wires, represented by the line 14, so that while the same porosity is maintained, a smoother and flatter paper-formation surface is provided, upon which the fibres of the paper stock will form better, due to their tendency to span the spaces between the wires rather than to be drawn down into them.

In Figs. 5 and 6 I have shown a modification in which the woven wire is of twill weave, the square cross-sectional warp wire 10 being woven over one and under two of the circular cross-section weft wires. This type of weave provides a cloth in which there are long knuckles at the under or wear side, and according to my invention the square cross-section warp wires provide these long knuckles with a flat wearing surface which will have a very much longer wearing life than twill weave wires employing circular cross-section warp wires. As above pointed out the interlocking action produced by the biting of the warp wires into the weft wires prevents the sleaziness usually present in twill weave wires.

In Fig. 8 I have shown a modification in which both the warp wires 10 and the weft wires 15 are of square cross-section, the warp wires being woven with the ordinary type of weave going over one and under one weft wire. This makes for increased wearing surface in the weft wires.

In Fig. 9 I have shown a modification in which the weft wires 16 are of rectangular cross-section, the longer dimension extending longitudinally of the cloth. This makes for a flatter weave and also increased wearing surface in the weft wires. In Fig. 10 I have shown the weft wires 17 of oval cross-section, the long dimension extending longitudinally of the cloth. This also makes for flatter weave and increased wearing surface in the weft wires.

In Fig. 11 I have shown instead of single weft wires weft wires 18—18 of relatively small diameters, each pair being woven as a single weft.

This makes for a flat weave and increased wearing surface in the weft wires.

In Fig. 12 I have shown the use of twisted cable weft wires 19 the cable being preferably twisted from four strands. This type of weft lends itself to flatness of weave as it will be compressed at the knuckles, has better drainage characteristics as it can be brought closer to the paper formation surface it produces less wire mark.

In Figs. 13, 14, 15, 16 and 17 I have respectively shown the square cross-section weft wires 15, the rectangular cross-section weft wires 16, the oval cross-section weft wires 17, the double weft wires 18—18, and the twisted cable weft wires 19 woven into twill weave wire cloth, the warp wires going over one and under two of the weft wires.

It will be understood that the paper-making wire, according to my invention, may be employed either in the form of a belt on Fourdrinier machines, or as cylinder on cylinder machines, or in any other suitable manner.

I have illustrated and described preferred and satisfactory embodiments of the invention, but it will be obvious that changes may be made therein, within the spirit and scope thereof, as defined in the appended claims.

Having thus described my invention what I claim and desire to secure by Letters Patent is:—

1. Woven wire fabric for paper making machines comprising interwoven warp and weft wires with knuckles produced in both the warp and weft wires, the warp wires throughout their length being of substantially square cross-section, the weft wires being of circular cross-section, the warp wires being embedded at their corners in said weft wires by reed-produced blows on said weft wires whereby the weft knuckles extend between the side surfaces of said warp wires to bring said weft knuckles closer to the surface of the fabric and to lock the weft wires against twisting relatively to the warp wires, the lower warp knuckles projecting substantially below the plane of the weft knuckles.

2. Woven wire fabric for paper making machines comprising interwoven warp and weft wires with knuckles produced in both the warp and weft wires, the warp wires throughout their length being of substantially square cross-section, and being embedded at their corners in said weft wires by reed-produced blows on said weft wires, whereby the weft knuckles extend between the side surfaces of said warp wires to bring said weft knuckles closer to the surface of the fabric and to lock the weft wires against twisting relatively to the warp wires, the lower warp knuckles projecting substantially below the plane of the weft knuckles.

3. Woven wire fabric for paper making machines comprising interwoven warp and weft wires with knuckles produced in both the warp and weft wires, the warp wires being carried over one and under a plurality of weft wires, the warp wires throughout their length being of substantially square cross-section and being embedded at their corners in said weft wires by reed-produced blows on said weft wires, whereby the weft knuckles extend between the side surfaces of said warp wires to bring said weft knuckles closer to the surface of the fabric and to lock the weft wires against twisting relatively to the warp wires, the lower warp knuckles projecting substantially below the plane of the weft knuckles.
